ANTENNA

Richard Cameron, Buffalo, N. Y.

Application July 27, 1927, Serial No. 208,788

1 Claim. (Cl. 250—33)

This invention relates to communication by means of radiant energy, and particularly to antennæ for radio telephone and telegraph receiving and sending apparatus. It is further in the 5 nature of an improvement upon the invention disclosed in my prior copending application Serial No. 154,416, filed December 13, 1926.

An object of this invention is to improve, simplify, and make more practical antennæ of the 10 type disclosed and claimed in my said prior copending application.

Another object of the invention is to provide an improved antenna with which the intensity of signals obtained will be a maximum on all 15 of the broadcasting ranges of wave lengths or frequencies; and with which tuning of the antenna circuit may be broadened without loss of signal strength.

A further object of the invention is to provide 20 an improved antenna for accomplishing each of these objects, which will be exceptionally compact; which will require a minimum of material for construction; which may be easily assembled by inexperienced persons and without the use of 25 tools; which will give a maximum of signal strength, and which may be taken down in a simple manner, when desired, for shipment.

A further object of the invention is to provide 30 an improved antenna which may be packed, shipped and sold in a knocked-down condition, and easily assembled by the purchaser without special tools, and which will be relatively inexpensive.

Various other objects and advantages will be 35 apparent from the following description of an embodiment of the invention, and the novel features will be particularly pointed out in the appended claim.

In the accompanying drawing:—

40 Fig. 1 is a perspective of an antenna constructed in accordance with the invention;

Fig. 2 is a sectional elevation of the same;

Fig. 3 is a perspective of the supporting member 45 by which the arms are attached to the main post; and

Fig. 4 is a plan of the same.

In the illustrated embodiment of the invention, a post or standard 1 is utilized as the main support, and for that purpose may be attached at 50 its lower end in any suitable manner to a supporting object, such as the peak of a roof, as shown by dash lines in Fig. 1. A supporting, or arm attaching, member shown separately in Figs. 3 and 4 is provided with a central aperture 3 of 55 a size and shape to fit closely over the upper end

of the post 1 and slide along the same to a position intermediate the ends of the vertical post, as shown in Figs. 1 and 2.

This member 2 is provided with a plurality of 60 sockets 4 opening outwardly and laterally therefrom in opposite directions, so as to radiate from the post 1 upon which the supporting member may be fitted. These sockets 4 may be formed in lateral extensions of the member 2 and are of a size to receive, with a tight fit, ends of radiating arms 5, so that the arms will be supported 65 by the member 2 and the post 1, and radiate in a plurality of opposite directions from this main post 1. The supporting member 2 may be in the form of a casting, and for simplicity the sockets 70 4 may open into the central passage 3. To provide the necessary strength, webs 6 may be provided between the sides of adjacent extensions for the sockets 4.

The posts 1 and the arms 5 may all be provided 75 with transverse grooves or slots 7, these slots being oblique to the face in which they are cut, and being inclined somewhat towards the supporting member 2 on the post 1. That is, all of 80 the grooves or slots 7 provided on the post 1 above the supporting member 2 will extend inwardly and downwardly, and those below the member 2 will extend inwardly and upwardly. Similarly, those in each arm 5 will extend inwardly and toward the center, that is, toward the post 1. 85

It will be noted that the arms 5 extend in opposite directions from the post 1, and each pair of oppositely extending arms cooperates with the post to support a loop or coil 8 formed by winding thereon an electrical wire or conductor 9. 90 Since four radiating arms have been illustrated by way of example as the preferred embodiment, the slots 7 in one face of the post will cooperate with the slots 7 in one face of oppositely extending arms 5, and the slots 7 of the other face of 95 the post will cooperate with the slots in the other pair of arms 5 for the support of another loop or coil 8 which extends, in this particular example, at right angles to the first coil or loop 8 which is mounted upon the other arms and the post. 100 The conductor or wire 9 forming each loop or coil 8 is preferably provided with suitable insulation, preferably one which is weatherproof when exposed to outside atmosphere and storms, and the slots or grooves 7 are of such a width that this 105 wire or conductor 9 will fit rather snugly or tightly therein when forced laterally into the same.

One end of each wire or conductor 9 is suitably anchored, such as providing a knot in the end of the same and the wire started through one 110

of the slots 7 in the post, or one of the arms 5, near the support member 2, that is, in the center of a desired loop or coil. Each wire or conductor 9 is then wound in a substantially vertical plane by attaching it to the arms of one of the pairs of arms 5 and the post, successively so that the wire will be wound progressively from an inner point outwardly, as shown in Fig. 2.

In the loop or coil 8 shown in elevation in Fig. 10, 2, the wire or conductor 9 is anchored in the slot or groove 7 in the front face of a post 1 just above the supporting member 2, extends therefrom laterally, and passes through the slot or nearest groove 7 in an adjacent arm 5, thence downwardly through the groove 7 in the same face of the post 1 at a point nearest the center, and so on, between the arms and post progressively, the terminal end of the wire or conductor 9 being secured in the last groove or slot 7 through which it passes. This last end may be anchored also in any suitable manner, such as by a knot in the conductor. Since the wires 9 are forced into the slots or grooves rather snugly and are drawn taut, the successive turns or stretches of the wire will 25 be held out of contact with one another, and by their tautness will hold the arms 5 within the sockets 4, and the member 2 against endwise movement along the post 1.

The other loop or coil 8 utilizing the other pair 30 of arms and the post 1 is wound in a similar manner, the two planes of the coils and loops intersecting one another at approximately right angles to one another so as to be in more or less inductive relation to one another, although both coils 35 or loops are conductively open. The outer ends of the wires of the two loops may be connected by lead wires 10 to a common lead-in wire or conductor 11 running to any radio set (not shown), so that the two conductively open coils are in 40 effect connected in parallel to one another at one end, and are also in more or less inductive relation to one another.

The arms 5 are also preferably of greater length than the wire supporting sections of the post 45 above and below the intermediate point of the post at which the support member 1 is located, so that the two coils or loops 8 which are formed will have considerably greater breadth or horizontal spread than height or vertical spread, the 50 coils in effect resembling vertical rhomboids with their major axes or diagonals approximately horizontal. When the vertical dimensions of the coils or loops are equal to or greater than the horizontal dimensions, I have found that great 55 signal strength is obtained on the wave lengths from approximately 400 meters up, but that the signal strength is not so great on wave lengths below approximately 400 meters. I have further found that by forming the coils with a horizontal 60 width or spread greater than their vertical height or spread, great signal strength is obtained for waves of the lower wave lengths of the present broadcasting bands, that is of the wave lengths below approximately 400 meters, and without loss 65 of strength for waves above 400 meters in length.

One difficulty with antenna, such as disclosed in said prior copending applications, has been the great sharpness in tuning, which in many cases was so great that users of radio receiving sets equipped with this invention would be unable to tune in certain stations. I have found that by increasing the horizontal spread of the coils or loops in accordance with this invention, the tuning is broadened, and as a result, the 70 users of radio sets equipped with such improved

antenna are able to pick up many stations which they formerly passed over unknowingly because of the previous great sharpness of tuning.

If the loops are of equal, vertical and horizontal spread, I have found that considerably more wire must be used in order to have turns in the loops or coils sufficient to obtain desired volume or signal strength, and this has made the tuning of one dial receiving sets entirely too sharp for the average, unskilled operators of such sets. By providing greater horizontal spread and cutting down the vertical spread of the loops or coils, in accordance with this invention, I am able to decrease the amount of wire required for each loop which not only reduces the cost of the antenna, but broadens the tuning without material loss in signal strength. An antenna of this type receives equally well, radio signal waves coming from all directions.

It will be observed that since the only connection required between the post and the arms is the supporting member 2, the arms, posts, the supporting member 2, and the stretches of wire for the two coils or loops may be advantageously sold and shipped as a knock-down or unassembled outfit in a very compact package. To assemble such an outfit, the purchaser merely places the supporting member 2 over the post 1 and slides it into the intermediate position shown in Fig. 2, between the upper and lower sets of slots or grooves 7 thereof. The arms are then inserted in the sockets 4, the stretches of wire wound upon the arms 5 and the post 1 to form the two coils or loops, after which the lead-in connections 10 from the common lead-in wire 11 may be attached. During such assembly no tools are required, and since the wire of the loops or coils is of the insulated type, the use of special insulators on the arms and posts will be unnecessary. Such an antenna is exceptionally inexpensive for 115 the reason that the post 1 and the arms 5 may be made of wood or other inexpensive material, the supporting member 2 may be a single casting of suitable metal, such as aluminum.

In addition to the above features, the improved 120 antenna herein disclosed includes a special relation between the conductors and also in connection with the support. The coil convolutions of each conductor lie in the same plane and have a common axis, while the axes of both conductors lie in the same plane in crossed angular relation. These conductors are further spaced and independent of each other and have corresponding coils arranged in adjacent crossed relation, the respective coils of each conductor being inter- 130 threaded relative to one another in order to secure the adjacent crossing of corresponding convolutions.

It will be further noted that the post or standard 1 is specially constructed so that it has a 135 plain central or intermediate portion over which the socket member is positioned, while the standard at opposite sides of this portion is provided with slots inclined toward this central portion. Two groups of slots are formed in the standard 140 in this manner, one group facing laterally from the other and arranged in offset relation thereto. The special construction of the socket member also forms a principal feature of the invention in conjunction with the special structure of the standard and the supporting arms, resulting in the production of a special combination of parts from which a support for the coiled conductors disclosed herein can be formed in a very simple and expedient manner, each part cooperating 145 150

with the other to facilitate the convenience and simplicity of construction and assembly of the antenna.

It will be understood that various changes in the details, which have been herein described and illustrated in order to explain the nature of the invention, may be made by those skilled in the art within the principle and scope of the invention as expressed in the appended claim.

10 I claim as my invention:

A radio antenna comprising a supporting post, a socket member detachably surrounding an intermediate portion of said post, a plurality of arms extending radially from said post and hav-

ing the inner end of each slidably received in said socket member and abutting said supporting post, and wire conductors forming a winding directly connected alternately to one of said arms and to said post at opposite sides of said socket member and extending between said arms and post in diagonal relation at spaced intervals from said socket member, said wire conductors forming a retaining means holding said arms engaged in said socket member with inner ends against said supporting post to retain said socket member on said post in assembled relation.
